CASTING ROD

Leonard Bruce, New Castle, Ind.

Application May 1, 1943, Serial No. 485,349

4 Claims. (Cl. 43—19)

The present invention relates to new and useful improvements in casting rods, and has for its primary object to provide, in a manner as hereinafter set forth, a device of this character comprising unique mechanical means whereby longer and more accurate casts may be made with less effort.

Other objects of the invention are to provide a mechanical casting rod of the aforementioned character which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a casting rod constructed in accordance with the present invention.

Figure 2 is a view in vertical longitudinal section through the device.

Figure 3 is a view in side elevation with a portion broken away in section, showing the device ready to make a mechanical cast.

Figure 4 is a cross-sectional view, taken substantially on the line 4—4 of Figure 1.

Figure 5 is a cross-sectional view, taken substantially on the line 5—5 of Figure 1.

Figure 6 is a view partly in side elevation and partly in vertical section, showing another form of the invention.

Figure 7 is an enlarged view in vertical longitudinal section through a portion of the modification.

Referring now to the drawings in detail, it will be seen that reference numeral 1 designates a tubular rod of suitable length, diameter and material. Mounted longitudinally on one end portion of the rod 1 is an elongated handle 2. The handle 2 has extending thereinto from its forward end a socket, or bore, 3 which accommodates the rod 1.

• A tubular, tapered arm 4 is hingedly mounted at 5 on the forward end portion of the rod 1 for swinging movement in a vertical plane. Coacting latch elements 6 on the hingedly connected ends of the rod 1 and the arm 4 releasably secure the latter in longitudinal alignment with the former.

A wire rod 7 is operable in the tubular rod 1 and is pivotally connected at 8 to the hinged end 50

portion of the arm 4. A head 9 is fixed on the rear end of the rod 7 for sliding movement in the tubular rod 1. The rod 7 is slidable through an abutment 10 in the tubular rod 1. The abutment 10 is spaced forwardly from the rear end of the tubular rod 1. A coil spring 11, which is under tension at all times, encircles the wire rod 7 between the members 10 and 9 for actuating the arm 4 and for yieldingly holding same in longitudinal alignment with the tubular rod 1.

A trigger 12 is pivotally mounted at 13 in the handle 2 for engagement behind the head 9 (see Fig. 3) for holding the arm 4 in an angular position through the medium of the rod 7 when a mechanical cast is to be made. A coil spring 14 is engaged with the trigger 12 for engaging said trigger behind the head 9. The trigger 12 is operable in slots 15 which are provided therefor in the tubular rod 1, and the lower portion of the handle 2.

It is thought that the operation of the device will be readily apparent from a consideration of the foregoing. Briefly, when a manual cast is to be made in the usual manner, the arm 4 is permitted to remain in longitudinal alignment with the tubular rod 1, in which position it is secured by the coacting latch elements 6 with the assistance of the coil spring 11. When a mechanical cast is to be made, the arm 4 is swung upwardly on the hinge 5, thereby disengaging the latch elements 6 and pulling the wire rod 7 forwardly for compressing the spring 11. When the head 9 clears the trigger 12, the spring 14 engages said trigger behind said head. As the cast is made, the trigger 12 is pulled and disengaged from the head 9. The coil spring 11 then actuates the arms 4 through the medium of the wire rod 7 for swinging the arm 4 forwardly and downwardly in a manner to materially increase the distance of the cast. The adjacent ends of the members 1 and 4 are provided, respectively, with closures 16 and 17. The closure 17 is slotted to accommodate the pivotal connection 8 of the wire rod 7. The closure 16 is slotted for the passage of the wire rod 7.

In the embodiment illustrated in Figure 6 of the drawings, there is shown a handle 18 of the type comprising a drop reel seat 19. A trigger 20 is pivotally mounted at 21 in the rear leg of the reel seat 19. Forwardly of the reel seat 19, a secondary trigger or dog 22 is pivotally mounted at 26 in the handle 18 for engagement behind the head 9. A flexible strand 23 operatively connects the trigger 20 to the secondary trigger or dog 22 for actuating the latter to inoperative

position against the tension of its coil spring 26. The flexible strand 23 is operable in a passage 25 which is provided therefor in the handle 18. In other respects this modification is substantially similar in construction and operation to the embodiment illustrated in Figures 1 to 5, inclusive, of the drawings.

It is believed that the many advantages of a casting rod constructed in accordance with the present invention will be readily understood, and although preferred embodiments of the device are as illustrated and described, it is to be understood that further modifications and changes in the details of construction may be resorted to which will fall within the scope of the invention as claimed.

What is claimed is:

1. A fishing pole comprising a tubular rod, a handle on one end portion of said rod, an arm hingedly mounted on the other end of the rod, a member operable in the rod and pivotally connected to the arm for actuating same in one direction, and a coil spring in the rod operatively connected to said member for actuating same.

2. A fishing pole of the character described comprising a tubular rod, a handle on one end portion of said rod, an arm hingedly mounted on the other end portion of the rod, an operating rod slidable in the first-named rod and pivotally connected to the hinged end portion of the arm, a coil spring in the tubular rod operatively connected to said operating rod for actuating same for swinging the arm in one direction, a manually operable trigger in the handle for releasably securing the operating rod against movement under the influence of the coil spring, and means for releasably securing the arm against swinging movement on the tubular rod.

3. A fishing pole of the character described comprising a tubular shaft, a handle on one end portion of said tubular shaft, an arm hingedly mounted on the other end portion of the tubular shaft, a rod operable in the tubular shaft and pivotally connected to the hinged end portion of the arm, an abutment in the tubular shaft, the rod being slidable through said abutment, a head on one end portion of the rod, a coil spring mounted under tension between the abutment and the head for actuating the rod for swinging the arm in one direction, and a manually operable, spring-pressed trigger pivotally mounted in the handle and engageable with the head for releasably securing the rod against actuation by the coil spring.

4. A fishing pole of the character described comprising a tubular shaft, a handle on one end portion of the tubular shaft, said handle including a drop reel seat, a tubular arm hingedly mounted on the other end portion of the shaft, a rod operable in the shaft and pivotally connected to the hinged end portion of the arm, a head on the rod operable in the shaft, a coil spring in the shaft engaged with the head for actuating the rod for swinging the arm in one direction, a manually operable trigger pivotally mounted on the reel seat of the handle, a spring-pressed secondary trigger pivotally mounted in the handle and engageable with the head for releasably securing the rod against actuation by the coil spring, the handle having a passage therein extending between the triggers, and a flexible strand operable in the passage and operatively connecting the first-named trigger to the second-named trigger.

LEONARD BRUCE.
